SPACE CONDITION RESPONSIVE INSTRUMENT

Henry Dreyfuss, South Pasadena, Calif., assignor to Minneapolis-Honeywell Regulator Company, Minneapolis, Minn., a corporation of Delaware

Filed Feb. 24, 1960, Ser. No. 59,497

Term of patent 14 years

(Cl. D52—7)

FIG. 1

FIG. 3

FIG. 2

Figure 1 is a front perspective view of a space condition responsive instrument embodying my new design;

Figure 2 is a top partially cutaway view of the instrument taken on line 2—2 of Fig. 1, and

Figure 3 is a side view of the instrument shown in Figure 1 looking toward the right side of Figure 1.

I claim:

The ornamental design for a space condition responsive instrument, substantially as shown.
